UNITED STATES PATENT OFFICE.

GEORGE WASHINGTON NEWMAN, OF CHICAGO, ILLINOIS, ASSIGNOR TO WILSON-JONES
LOOSE LEAF COMPANY, A CORPORATION OF ILLINOIS.

LOOSE-LEAF BINDER.

Application filed October 20, 1922. Serial No. 595,711.

To all whom it may concern:

Be it known that I, GEORGE WASHINGTON NEWMAN, a citizen of the United States, and a resident of the city of Chicago, in the county of Cook and State of Illinois, have invented certain new and useful Improvements in a Loose-Leaf Binder; and I do hereby declare that the following is a full, clear, and exact description of the same, reference being had to the accompanying drawings, and to the numerals of reference marked thereon, which form a part of this specification.

This invention relates to a loose leaf binder of that type in which the upper cover is removably and adjustably latched to the leaf-impaling posts; and it is an object of this invention to generally improve this type of binder and provide a novel method of assembly, especially in relation to the actuating means for opening and closing the binder.

With these and other objects in view, which will become more apparent in the following description and disclosures in the drawings, this invention comprises the novel mechanism and combinations hereinafter described and more particularly pointed out and defined in the appended claims.

In the accompanying drawings which illustrate a preferred embodiment of this invention and in which similar reference numerals refer to similar features in the different views:

Figure 1 is a top plan view of a completed binder involving this invention.

Figure 2 is an enlarged broken vertical section through the upper clamping member.

Figure 3 is an enlarged horizontal and broken section through the upper clamping member with parts removed.

Figure 4 is an enlarged fragmentary vertical section of the upper clamping member taken substantially upon the line 4-4 of Figure 3.

Figure 5 is a fragmentary enlarged section upon the line 5-5 of Figure 4.

Figure 6 is a section upon the line 6-6 of Figure 4.

Figure 7 is an enlarged fragmentary section of the upper clamping member showing the method of securing the operator to the actuator.

As shown on the drawings:

In the exemplification of this invention, there is illustrated a binder in which the leaves are impaled upon a pair of spaced posts 1 which are suitably secured to the lower cover or to a clamping member hinged to the lower cover as is common in the art. The upper cover 2 is hinged to a hollow clamping member 3 preferably made of sheet metal with its ends closed by cap members 4. Suitable apertures are provided in this upper clamping member for receiving the impaling posts which are shown as extending therethrough.

Frictional latching mechanism is concealed in the hollow clamping member 3 for frictionally locking the same with its attached cover to the impaling posts, and an actuator for unlatching or releasing said mechanism is also housed within said clamping member and operable by means of a stud or finger piece projecting through said clamping member.

The frictional latching mechanism for each post comprises an apertured lever 5 through which the post passes. In the present instance, the lever 5 is fulcrumed at an intermediate point and its two arms are inclined downwardly, so that the apertured arm will have an oblique position with respect to the post in order to frictionally bind against the same. The power arm of said lever is yieldingly urged in its normal position for increasing the obliquity of its apertured end for applying the frictional or braking action to its impaling post. For accomplishing this purpose, the lever 5 is provided with a slot or aperture at its fulcrum point which fits over a projection 6 on a fulcrum which constitutes one side or wall of a small square box 7 or the like, in which a coil spring 8 is housed, as shown in Figure 4, that bears upwardly against the power arm of the lever, and normally forces the apertured end downwardly, thuswise in-

creasing its obliquity with relation to the post for frictionally latching or binding the same to the upper clamping member. Each small box is provided with spaced apertures 9 in its bottom as shown in Figure 6, and the bottom of the clamping member is punched upwardly into these apertures in order to anchor the box in position. In the particular structure illustrated, one box 7 is positioned beyond the outer side of its post and the lever 5 extends inwardly, while the other box 7 is positioned beyond the inner side of its post and its lever 5 extends outwardly. This is for the purpose of allowing the actuator 10 to simultaneously actuate or release the levers 5 when it is desired to adjust or remove the cover 2.

The actuator consists of a narrow metal plate having its ends bifurcated, or provided with spaced tines adapted to receive the impaling posts 1 therebetween. The tines at one end of the actuator are bent upwardly near their ends and then slope downwardly to provide cams 11, while the tines at the other end of the actuator have upwardly sloping portions or cams 11^a that are bent downwardly at right angles at their ends to form supporting legs or rests. These cams are so positioned on the actuator that a sliding movement of the actuator to the right as viewed in Figure 2 will cause the cams to ride under the levers 5 and raise the same sufficiently to release them from frictional binding or braking action with respect to the impaling posts.

The actuator is operated by means of a stud or finger piece 12 extending through a slot 13 in the clamping member 3 and secured at its lower end to the actuator 10 by a novel method. As shown, the actuator 10 normally rests upon the bottom of the clamping member, but it is provided with an upwardly offset portion adjacent the slot 13 in which the finger piece is secured.

As the actuator should be made from a thin and light strip of metal, much difficulty has been encountered in firmly securing the finger piece therein when the actuator has already been positioned in the clamping member. According to my novel method of assembly, the actuator with a proper size hole in the offset portion is properly positioned within the clamping member, the stud 12 is then inserted through the slot 13, and its lower end inserted in the aperture in the offset portion of the actuator. The stud is preferably provided at its lower end with a reduced portion or neck that extends some distance through the aperture for the purpose of crimping or expanding the same over the adjacent surface of the actuator by a tool insertable through the aperture 14 in the lower side of the clamping member. The stud will accordingly be securely anchored to the actuator between the annular shoulder

framed by the reduced neck and the swedged over end. It will of course be understood that the clamping member and its contained parts are completely assembled before the same is applied to the binder.

The operation of the binder is clearly obvious and requires merely a shifting of the actuator to the right for unlocking or releasing the levers 5 by raising the same against the tension of the springs 8. The levers may be held in such released position by the cams 11 and 11^a, while the cover 1 is adjusted or removed. When it is desired to again lock the cover in position, it is merely necessary to shift the actuator to the left to bring the cams out of engagement with the levers 5, when the springs 8 will automatically operate the levers into frictional engagement with the impaling posts.

It will accordingly be apparent that my invention produces an efficient and superior binder that can be readily assembled, and in which the metal parts may be made of light and thin material readily stamped into shape, so that a light and cheap structure may be produced, but one which is very durable for the service to which it is adapted.

I am aware that numerous details of construction may be varied through a wide range without departing from the principles of this invention, and I therefore do not purpose limiting the patent granted otherwise than necessitated by the prior art.

I claim as my invention:

1. In a loose leaf binder, a pair of impaling posts, a cover having a clamping member provided with apertures for receiving said posts, levers fulcrumed intermediate their ends in said member and having downwardly inclined arms, one arm of each lever frictionally engaging said posts, springs yieldingly acting against the other arms, and an actuator for releasing said levers from frictional engagement with said posts.

2. In a loose leaf binder, a hollow clamping member having a post-receiving aperture therein, a lever having an opening concentric with said aperture, a box having a fulcrum upon one side for supporting said lever intermediate its ends, with one end extending into said box, and a spring confined within said box and bearing against said lever for the purpose set forth.

3. In a loose leaf binder, a hollow clamping member, post-locking mechanism therein, an actuator having an aperture and located within said member for actuating said mechanism, a finger piece extending through said clamping member and into the aperture of said actuator, said clamping member having an aperture adapted for receiving a tool for expanding the end of said finger piece.

4. In a loose leaf binder, the combination with an impaling post, of a hollow clamping member having an aperture for receiving

said post, a box-like container in said member, a lever fulcrumed intermediate its ends upon said container, one arm of said lever frictionally engaging said post, a spring in
5 said container pressing against the other arm of said lever and an actuator for releasing said lever.

In testimony whereof I have hereunto subscribed my name in the presence of two subscribing witnesses.

GEORGE WASHINGTON NEWMAN.
